(57) **CLAIM**

I claim the ornamental design for brake pedals, as shown and described.

DESCRIPTION

FIG. 1 is a perspective view of brake pedals of a representative sample of a vehicle (unclaimed), with both pedals in a resting configuration.

FIG. 2 is another perspective view of the brake pedals of FIG. 1, separate from the vehicle.

FIG. 3 is a right side elevation view thereof.

FIG. 4 is a left side elevation view thereof.

FIG. 5 is a top plan view thereof.

FIG. 6 is a bottom plan view thereof.

FIG. 7 is a front elevation thereof.

FIG. 8 is a rear elevation thereof.

FIG. 9 is a perspective view of brake pedals of a representative sample of a vehicle (unclaimed), with both pedals in a second position.

FIG. 10 is another perspective view of the brake pedals of FIG. 9, separate from the vehicle.

FIG. 11 is a right side elevation view thereof.

FIG. 12 is a left side elevation view thereof.

FIG. 13 is a top plan view thereof.

FIG. 14 is a bottom plan view thereof.

FIG. 15 is a front elevation thereof; and,

FIG. 16 is a rear elevation thereof.

The broken lines shown represent unclaimed subject matter and form no part of the claimed design.
